H. YOST

ROOFING SEAM

Filed April 26, 1926

Henry Yost,
INVENTOR

BY Victor J. Evans

ATTORNEY

P. J. Hickey.

WITNESS:

Patented Feb. 22, 1927.

UNITED STATES PATENT OFFICE.

HENRY YOST, OF KENTON, OHIO.

ROOFING SEAM.

Application filed April 28, 1926. Serial No. 104,731.

The object of this invention is to provide improved means for securing flexible sheet roofing, so that an absolutely tight joint or seam, will be produced and indefinitely maintained without the use of paint or other material frequently employed for sealing the joints.

A further object is to provide a flat or slightly curved strip of rust-proof material with portions struck up therefrom, to form tongues or clinching devices so positioned that when the strips are secured to the upper surface of one sheet, the tongues may be forced thru the sheet directly above, near the overlapping edge thereof, said tongues being bent over beyond the lower edge of the strip and pressed down or clinched slightly below said edge, thereby curving or bending the edge of the roofing sheet, and causing the latter to closely contact with the sheet which it overlaps.

A further object is to provide a metallic strip curved slightly in a direction transversely of its length, so that the edges of the metallic strip will closely engage the roofing sheet when nailed down, the heads of said nails also being protected from the weather, since they will be covered by the sheet overlapping the nailed portions.

With the foregoing and other objects in view, the invention consists in the novel construction and arrangement of elements described, illustrated and claimed, it being understood that modifications may be made within the scope of the claims, without departing from the spirit of the invention.

In the drawings forming part of this application,

Figure 1 is a perspective view showing fragmentary portions of sheet roofing material in overlapping relation and showing a metallic strip having tongues or the like struck up therefrom and adapted to project thru the upper sheet and to be clinched in the manner indicated.

Figure 2 is a view in section on the line 2—2 of Figure 1.

Figure 3 is a section thru the metallic strip, one of the tongues projecting upwardly, and the head of the nail by means

of which the strip is to be secured, being partly driven home, so that it contacts with the surface of the metallic strip before this strip has been flattened out to cause the edges thereof to firmly grip the roofing sheet. 55

The lower sheet of roofing material is designated 10, and the upper or overlapping sheet is shown at 11, a metallic strip 12 being interposed between the sheets and spaced as shown from the lower edge of the upper 60 sheet. This strip 12 is curved transversely, as shown in Figure 3, before being nailed down, but during the process of nailing, the strip 12 is flattened out by the head 13 of the nail or nails 14, and firm engagement of 65 the sheet 10 by the edges of strip 12 is thereby secured or insured.

In the manufacture of the device, tongues 15 are formed by stamping out portions to form openings 16, and the particular location of the tongues or clinches is important, because it is desired to have the tongues project beyond the lower edge of strip 12 when said tongues are bent over. The bent over or deflected portions are shown at 18, 75 and it will be observed that because of the arrangement specified, a very close joint may be produced between the edge 11 of sheet 11 and the surface of sheet 10.

Having thus described the invention, what I claim is:

1. The combination with the overlapping portions of sheets of flexible roofing, of a metallic strip interposed between said portions, the strip including tongues projecting thru the upper sheet and bent over the lower edge of the strip, to bring the edge of the upper sheet into close contact with the surface of the lower sheet. 85

2. The combination with the overlapping portions of sheets of flexible roofing, of a metallic strip interposed between said portions, the strip including tongues projecting thru the upper sheet and bent over the lower edge of the strip, to bring the edge of the upper sheet into close contact with the surface of the lower sheet, said strip being of arch form, in a transverse direction, when applied, and securing devices passing thru the strip and the lower sheet and causing 100

the edges of the strip to firmly engage the lower sheet when the securing devices are forced to final position.

3. A metallic strip for securing overlapping portions of sheet roofing, the body of said strip being curved transversely and including tongues struck up from the main portion thereof, and positioned to be bent

over the edge of the strip in the direction of the curvature thereof for producing direct 10 and positive contact between the edge of the upper sheet and the surface of the lower sheet, the strip to be positioned between the sheets.

In testimony whereof I affix my signature.
HENRY YOST.
